UNITED STATES PATENT OFFICE.

ERNST FREDERICK WEBER, OF RIVERSIDE, ILLINOIS.

WINDSHIELD FOR RAILWAY MOTOR CARS.

Application filed February 1, 1926. Serial No. 85,211.

This invention relates to wind shields and particularly to wind shields designed primarily for use on railway motor cars.

These motor cars are used by section 5 hands, and it is desirable to protect the person operating the car, as much as possible, from the impact of the elements, by the use of a shield of one kind or another, and also to provide a shield which will give to 10 the operator a free and unobstructed view of the track ahead.

To the accomplishment of this purpose, my invention is directed, and it consists in the devices and combination of devices herein 15 illustrated, described and claimed.

In the drawings:

Figure 1 is a perspective view of a typical railway inspection car to which my invention has been applied.

20 Figure 2 is an end elevation, enlarged, showing the shield in proper position with relation to the other parts of the car.

Figure 3 is a front elevation of the same, partly broken away, the part of the car to 25 which the shield is fastened being shown in vertical section.

Figure 4 is a transverse, sectional view of one edge of the shield, the section being taken in the horizontal plane indicated by 30 the line 4—4 of Figure 3.

Figure 5 is a sectional view of a detail, the section being taken in the horizontal plane indicated by the dotted line 5—5 of Figure 3.

35 Figure 6 is a sectional view showing the bottom rod arrangement, the section being taken in the vertical plane indicated by the dotted line 6—6 of Figure 3.

Figure 7 is a perspective view, enlarged, 40 of a modification.

My invention is designed to be applied to the railway motor car illustrated as a whole, in Figure 1, by the letter A; said car being provided with a raised platform or operator's seat B, and, preferably, with a central, raised, hand-hold or rod C, extending longitudinally of the seat, in the median line of 45 the car. My wind shield is designated as a whole by the letter D.

50 Referring more particularly to Figures 2 to 6, inclusive, it will be understood that the shield D is formed of a fabric placed over the frame of metal, which comprises two side bars 1, 1, a top rod 2, and a lower rod 3, these parts of the frame being held together by bolts 4.

The side rod 1 is of conventional angle iron, as illustrated in Figure 4, and at its lower end is bent to form a supporting and securing extension arm 5. The rods 2 and 3 extend through suitable apertures in the side bars, as clearly shown, and over the frame I secure a suitable shield of fabric, such, for example, as the canvas 6.

The lower end of the fabric (see Fig. 6) 65 is folded around the rod 3 and secured by a line of stitches 7; the upper edge of the fabric 6 is folded and secured to the upper rod 2 by a line of stitches 8. The side edges are wrapped about the side bars 1, 1, as 70 clearly seen in Figure 4, and secured thereto by a line of stitches 9, 9.

The frame may be fastened to the car in such position as will be convenient for the operator. As herein shown, it is secured a 75 slight distance in rear of the front end of the seat B by bolts 10 passing through the arm 5 of the frame, and through the top of the seat.

Where the car has a rod C, or parts that 80 would otherwise interfere with the positioning of the shield, I find it convenient to slit the fabric 6 longitudinally and to sew to one slitted edge a flap 11, and to provide for fastening the flap to the other edge by 85 snap hooks or fasteners 12 of familiar, conventional form.

The side rods 1 will be bent to stand at an angle with respect to the securing arm 5, so that the shield will be inclined rearwardly. The side rods 1 will also be of 90 such length that when the frame is completed, the upper rod 2 will not extend above the seat B to such a height as to obscure the vision of an ordinary sized operator who 95 may sit on the seat B, behind the shield D.

From this it will be obvious that the operator, sitting behind the shield, will be protected from the action of the elements by the fabric 6 and at the same time will have a 100 free and unobstructed view of the track.

I am aware that wind shields of various types have been used, but the same have generally been provided with window glass or other transparent material, which of itself 105 more or less obscures the view of the operator, and which view is further obstructed when driving through rain, snow or sand storms. It will be observed that in my shield this does not occur and that the operator 110 has an unobstructed view of the track ahead. By inclining the shield slightly, rearwardly,

it is found that the impacting elements strike the shield and move outwardly and upwardly a sufficient distance away from the edges of the shield so as to leave the space 5 immediately in rear thereof comparatively clear. In other words, rain, snow and air do not impinge against the head of the operator.

The modification shown in Figure 7 permits of adjustment of the height of the fabric screen D. The side members 1 are provided with a plurality of apertures at their upper ends, as shown at 13, and the top bolt 2 may be inserted in any of the apertures desired. In this form, stitches 8 are omitted and the top of the fabric 6 secured by snaps and buttons as indicated at 14.

I claim as my invention:

1. A wind shield for railway motor cars comprising two metallic side frame members secured together at their ends by top and bottom rods and having their lower ends bent rearwardly and at an angle to the side frame members, means for securing the rearwardly bent ends to a motor car seat, the top of the shield when so secured being below the line of vision of the motorman, and a fabric covering the frame.
2. A wind shield for railway motor cars comprising two metallic side frame members secured together at their ends by top and bottom rods and having their lower ends bent rearwardly and at an angle to the side frame members, means for securing the rearwardly bent ends to a motor car seat, the top of the shield when so secured being below the line of vision of the motorman, and a fabric, secured by stitching, covering the frame.
3. A wind shield for railway motor cars comprising two metallic side frame members secured together at their ends by top and bottom rods and having their lower ends bent rearwardly and at an angle to the side frame members, means for securing the rearwardly bent ends to a motor car seat, where-

by the side members will incline upwardly from and rearwardly of the front of the support, the top of the shield when so secured being below the line of vision of the 50 motorman, and a fabric covering the frame.

4. A wind shield for railway motor cars comprising two metallic side frame members secured together at their ends by top and bottom rods and having their lower ends 55 bent rearwardly and at an angle to the side frame members, means for securing the rearwardly bent ends to a motor car seat, whereby the side members will incline upwardly from and rearwardly of the front of the support, the top of the shield when so secured being below the line of vision of the motorman, and a fabric covering the frame, the side frame members being of conventional angle or L-form in cross section. 65

5. A wind shield for railway motor cars comprising two metallic side frame members secured together at their ends by top and bottom rods and having their lower ends bent rearwardly and at an angle to the side 70 frame members, means for securing the rearwardly bent ends to a motor car seat, the top of the shield when so secured being below the line of vision of the motorman, and a fabric, secured by stitching, covering the 75 frame, and a slit in the fabric extending from one end towards the middle and a flap sewed to one margin of the slit and means for removably fastening the other margin and the flap. 80

6. A wind shield for railway motor cars, comprising a metal frame, means for attaching the frame angularly with respect to the motor car seat, a fabric screen on the frame, and cooperating means on the side 85 frame members and the top rod member for adjusting the latter with respect to the former to vary the height of the screen.

In testimony, that I claim the foregoing as my invention I affix my signature this 90 27th day of January, 1926.

ERNST FREDERICK WEBER.
